WILLIAM B. WALKER, OF ROXBORO, NORTH CAROLINA

APPARATUS FOR OPERATING ON SPINNING FRAMES AND OTHER MACHINES

Application filed June 3, 1925. Serial No. 34,572.

It has been a serious problem in spinning mills to prevent the formation of so-called bunches, slugs or gouts in the yarn, which are caused by the accumulation of minute particles of loose fibers, invisible fly, lint, and dirt on the work during the spinning operation. These bunches materially impair the quality of the yarn, and it has been estimated that they cause from twenty to thirty per cent of loom stoppages. The operators in every spinning mill are at constant war against the formation of these bunches and efforts to solve the problem have cost tremendous amounts of money and time. The common practice has been to frequently clean the machines by hand with brush and broom or by compressed air, but those methods are superficial and have little real cleaning value, except when the entire room is stopped and then only under careful hands. I have found, however, that the solution of this problem is in keeping the air over the machines free from these fine particles and thus prevent the accumulation thereof.

25 An object of my invention is to provide an apparatus for accomplishing this result.

The spinning frames are commonly arranged in the spinning room in rows, with the frames in each row arranged end to end. In connection with such arrangement of spinning frames and other machines, and with the above mentioned and other objects in view, my invention contemplates the provision of a method and an apparatus for carrying out the method whereby a stream of air may be directed downwardly and traversed over the machines of each row successively, the pressure of the air being sufficient to force the loose fibers, lint and dirt, away from the work and toward the floor in such a manner as to prevent adhesion or accumulation until after they pass beneath the work. Preferably the stream of air is of substantially the width of the machines and traverses widthwise over the length of the machines so that it operates uniformly over each machine and throughout the area thereof. In some instances it may be desirable, instead of directing a stream of air downwardly over the machines, to traverse suitable vacuum creating means over the ma-

chines so as to draw the dust and other fine particles from the machines and work and, accordingly, it is to be understood that, except as defined in the claims, certain features of my invention are not limited to a method or apparatus whereby the desired result is accomplished by downwardly directed currents of air.

In the embodiment of my invention illustrated in the drawings an endless track is arranged above the several rows of machines, and a blower is mounted to travel continuously along the track by power operated means so as to direct the stream of air downwardly over the several rows of machines successively, the blower thus traveling over each machine at predetermined intervals.

The several features of the invention will be clearly understood from the following description and accompanying drawings, in which,

Figure 1 is a sectional side elevation of a portion of an apparatus which is particularly adapted for use in carrying out my improved method;

Fig. 2 is a sectional view, partly in elevation, taken on the line 2—2 of Fig. 1;

Fig. 3 is a diagrammatical view, illustrating the manner in which the apparatus may operate upon a plurality of rows of spinning frames or similar machines;

Fig. 4 is a sectional plan view taken on the line 4—4 of Fig. 2;

Fig. 5 is a detail side elevation, partly in section, of the blower nozzle and associated parts;

Fig. 6 is a detail sectional view on an enlarged scale taken on the line 6—6 of Fig. 4; and

Figs. 7 and 8 are diagrammatical views illustrating the manner in which the blower nozzle is adapted to be adjusted to clear obstructions in its path of travel.

The apparatus illustrated in the drawings is particularly adapted for use in operating upon spinning frames, indicated at 2 in Fig. 3, which are commonly arranged in the spinning room in rows with the frames of each row arranged end to end. As shown in Fig. 3 the apparatus is provided with an endless

track 4 which extends centrally over the machines of each row. An air impelling device or blower 6 is mounted to travel along the track continuously by power operated means so as to operate successively upon the machines of each row, and upon the several rows of machines successively so that each frame is operated upon at predetermined intervals.

- 10 The track 4 is supported by means of hangers 8 having their upper ends secured to the ceiling 10 of the spinning room (Figs. 1 and 2). The air impelling device or blower 6 is provided with a carriage having flanged 15 wheels or sheaves 12 and 14 mounted upon the track, and is further provided with a fan 16 and an electric motor 18 having its shaft 19 arranged vertically. The motor 18, through suitable connections hereinafter described, drives the sheave 12 so as to propel the blower along the track, and also drives the fan 16. The fan 16 and motor 18 are enclosed by a sheet metal casing 20 which is made in two sections 21 and 22 that are welded together at 23. The upper section 21 is cylindrical, and the lower section 22 is suitably shaped to form a blower nozzle having its discharge orifice 24 of substantially the width of the spinning frames.
- 20 The driving sheave 12 is secured on one end of a horizontal shaft 26 which extends through and is journaled in suitable bearings in the bifurcated upper end of a vertically arranged post or hanger 28 forming a part 25 of the blower carriage. The connection between the sheave shaft 26 and the motor shaft 19 comprises a vertical shaft 30 which extends through suitable bearings in the post or hanger 28 and has its upper end connected 30 with the shaft 26 through bevel gears 32. The lower end of the vertical shaft 30 carries a spur gear 34 which operatively engages a pinion 36 secured on a vertical shaft 38 which extends through and is journaled in suitable 35 bearings in a depending post or hanger 40 which is cast integral with the post or hanger 28. The vertical shaft 38 is in axial alignment with the motor shaft 19 and is connected therewith through a suitable flexible coupling 40. The electric motor is supported by the hanger 40, by means of a spider 44 which has its hub secured by a set screw 46 to the hanger. The spider is provided with an outer annulus or rim 48 which is connected with the 45 hub by a series of four radial arms 50, and is further provided with depending bracket arms 52 having their lower ends bent inwardly to support radial lugs 54 projecting from the motor casing, the lugs being secured 50 to the bracket arms by bolts 56.

The annulus 48 of the spider supports the nozzle casing 20. To provide for this an annular member 55 is riveted to the inside of the upper end of the cylindrical section 55 21 of the casing and is provided with a hori-

zontal annular flange 57 that extends over the outer portion of the annulus 48. The flange 57 and annulus 48 are provided with opposed annular grooves forming a raceway for ball-bearings 59 so that the nozzle casing 70 may be turned or swiveled about a vertical axis as hereinafter described. The nozzle casing 20 is held so as to position its discharge orifice 24 transversely of the spinning frames during the normal operation of the blower by means of a series of three equally spaced rollers 60 which are received in notch-like recesses 62 in the flange 57. The rollers 60 are mounted on arms 64 which are pivotally mounted on upstanding brackets 66 secured to the annulus 48, and the rollers are pressed downwardly on the flange 57 by means of coiled springs 68 interposed between the free end of the arms and an abutment on the bracket members. The rollers 60 in addition to holding the casing in the desired position also serves to maintain the flange 57 down upon the ball-bearings 59. The portion of the annulus 48 that projects inwardly beyond the flange 57 tapers or is inclined downwardly and inwardly so as to direct the air entering the casing toward the blades of the fan 16.

The other sheave 14 is loosely mounted on the rear end of a rearwardly projecting bracket arm 70 secured to the upper end portion of the vertical post or hanger 28.

The fan 16 is of suitable construction so as to direct the air downwardly through the nozzle of the casing 20. As shown this fan is provided with a hub 72 secured on the upper end of the motor shaft 19 and with suitably formed blades 74 which are secured at their lower ends to an outwardly and downwardly flaring web 76 projecting from the fan hub 72, the upper ends of the blades being connected by a horizontally arranged annular sheet metal ring 78.

To energize the electric motor 18, trolley wires 80 are suitably mounted on blocks of insulating material 82 supported on the under side of the blower tracks 4. These trolley wires are engaged by trolley wheels 84 which are mounted on the free ends of arms 86 pivotally mounted on the upper ends of binding posts 88. Each trolley wheel is held up in engagement with its wire by means of a suitably arranged spring 90 engaging the under side of the arm. The binding posts 88 extend through apertures in a plate 92 of insulating material and are suitably secured therein. The plate 92 is secured on the upper end of one of the upstanding brackets 66. The lower ends of the binding posts are electrically connected with the motor by means of conductors 94.

With this construction it will be apparent that upon the current through the trolley wires being turned on, the motor shaft will drive the fan, and also through its con-

nection with the sheave 12 propel the blower continuously along the track. As the discharge orifice 24 of the blower nozzle extends completely across each machine over which it passes, the stream of air directed downwardly therefrom will act uniformly on all the machines throughout the length of each machine. The nozzle is arranged a suitable distance above the tops of the machines and the blower is propelled at proper speed and the stream of air is delivered from the blower under sufficient pressure to insure the air for a distance above the machines being maintained free from lint and other particles of foreign matter thus preventing accumulation on the machines or work.

In order for the broad nozzle to pass belts, posts or other obstructions at the ends of the machines, a means is provided for turning the nozzle on the ball-bearings 59 so as to cause it to travel edgewise. In Fig. 7 of the drawings, the nozzle is shown as being thus turned so as to clear a driving belt 96 at the end of the spinning frame. To provide for this a horizontally arranged abutment guide rod 98 is suitably arranged in the path of a vertical stud or roller 100 mounted upon the rim 55 of the nozzle casing. This guide bar is constructed and arranged so that upon engagement of the roller 100 with the curved forward end 102 thereof, the nozzle will be turned substantially 90° so as to cause it to travel edgewise by the belt, the rollers 60 riding out of the notches 62. When the nozzle has passed the belt and the roller 100 has cleared the end of the bar 98, it is returned to its initial transverse position by coiled springs 104 which are arranged diametrically opposite each other and have their inner ends secured to the lower end of the arms 52 of the spider, and their outer ends secured to the lower portion of the blower nozzle, the springs extending across the wider portion of the nozzle. The return movement of the nozzle by the action of the springs 104 is arrested by the engagement of the ratchet pawl rolls 60 in their respective notches 62.

In case it is necessary to turn the blower nozzle a distance less than 90° as indicated by broken lines in Fig. 8 of the drawings, an abutment bar 106 may be employed. This bar is so arranged that instead of the roller 100 engaging the inner side thereof as is the case with the bar 102 above described, the roller 100 rides over the outer side thereof, and the bar is so positioned as to cause the nozzle to be turned the required degree and to be held in that position until it passes by the obstruction and the roller 100 rides off of the rear end of the bar.

As will be evident to those skilled in the art, my invention permits various modifications without departing from the spirit thereof or the scope of the appended claims.

What I claim is:

1. Apparatus for operating upon spinning frames and other machines arranged in rows with the several rows arranged side by side having, in combination, an endless track arranged above the rows of machines, a carriage mounted to travel along the track, means mounted on the carriage for creating a current of air a distance above the machines and directing the air downwardly over the machines, and means for driving the carriage along the track so as to cause each machine to be operated upon at predetermined intervals to uniformly maintain the machines and the atmosphere above the machines substantially free from dust and other fine particles.

2. An apparatus of the class described having, in combination, an overhead track, a carriage mounted on the track, an electric motor mounted on the carriage having its shaft arranged vertically, a fan mounted upon the upper end portion of said motor shaft, a casing enclosing said fan and motor having its upper end open and having a nozzle formed on its lower end for directing a stream of air downwardly, and electrical connections for driving the motor comprising an overhead trolley conductor and a trolley mounted on the carriage.

3. An apparatus of the class described having, in combination, an overhead track, a carriage mounted to travel along the track, an electric motor mounted on the carriage below said track having its motor shaft arranged vertically, a fan mounted upon the upper portion of said motor shaft so as to be rotated thereby, a wheel mounted on the track from which said carriage is suspended, suitable connections between said motor shaft and wheel for propelling the carriage along the track, and a nozzle having its discharge orifice arranged beneath said motor and fan for directing a stream of air downwardly as the carriage is propelled along the track.

4. An apparatus of the class described having, in combination, an overhead track, a blower mounted to travel along the track, a nozzle for the blower adapted to direct a stream of air downwardly, and means for adjusting the angular position of the nozzle about a substantially vertical axis as the blower travels along the track.

5. An apparatus of the class described having, in combination, an overhead track, a carriage mounted to travel along the track, a blower mounted on the carriage, a nozzle for the blower mounted on the carriage and adapted to be turned about a vertical axis to adjust the angular position of the outlet end thereof, an abutment mounted on said nozzle, a stationary abutment adapted to be engaged by said nozzle abutment during the travel of the carriage along the track to effect said adjustment of the nozzle, and means for re-

turning the nozzle to its initial position upon disengagement of said abutments.

6. An apparatus of the class described having, in combination, an overhead track, a carriage mounted for movement along the track, a blower mounted on the carriage, a blower nozzle having its discharge orifice relatively long and narrow for directing a stream of air downwardly, a stationary abutment arranged in the path of said nozzle for changing the angular position of the nozzle about a vertical axis upon engagement of the nozzle therewith, and means for returning the nozzle to its initial angular position upon disengagement from said abutment.

7. Apparatus for operating upon machines arranged in a row having, in combination, a track arranged above the row of machines, a carriage mounted on the track, an electric motor mounted on the carriage having its shaft arranged vertically, a fan mounted upon the upper end portion of said motor shaft, a casing enclosing said fan and motor having its upper end open and having a nozzle on its lower end for directing a stream of air downwardly, electrical connections for energizing said motor, and means connected with said motor shaft for driving the carriage along the track.

8. Apparatus for operating upon machines arranged in a row having, in combination, a track arranged above the row of machines, a wheel mounted to travel along the track, a carriage suspended from said wheel, an electric motor having its shaft arranged vertically, a fan mounted on said shaft and arranged below said track, and driving connection between said motor shaft and said wheel.

9. Apparatus for operating upon machines arranged in a row having, in combination, a track arranged above the row of machines, a wheel mounted to travel along the track, a carriage suspended from said wheel, an electric motor having its shaft arranged vertically, a fan mounted on the upper end portion of said shaft, and driving connection between said shaft and said wheel.

10. Apparatus of the class described having, in combination, an overhead track, a blower mounted to travel along the track, a relatively wide nozzle for the blower for directing a stream of air downwardly and adapted to be turned to cause it to be positioned either transversely or longitudinally of its direction of travel, and means for thus changing the position of the nozzle as the blower travels along the track.

11. Apparatus for operating upon machines arranged in rows with the several rows arranged side by side having, in combination, an endless track arranged above the rows of machines, a carriage mounted to travel along the track, a blower mounted on the carriage provided with a casing having

its upper end open and having its lower end provided with a nozzle for directing a stream of air downwardly over the machines as the carriage travels along the track, and means for driving the carriage along the track so as to cause each machine to be uniformly operated upon at predetermined intervals.

12. Apparatus for operating on spinning frames and other machines arranged in rows with the several rows arranged side by side and spaced apart having, in combination, a blower having a casing having its upper end open and its lower end provided with a nozzle for directing a stream of air downwardly, and means for supporting the blower above the machines and traversing it in an endless path successively over the machines of the several rows so as to cause the stream to operate uniformly on each machine at predetermined intervals.

In testimony whereof, I have signed my name to this specification this 1st day of June, 1925.

WILLIAM B. WALKER.
